SAMUEL TIMSON AND HARRY MORLEY TIMSON, OF LEICESTER, ENGLAND, ASSIGNEES
OF ONE-HALF TO THOMAS MORLEY AND FREDERICK WILLIAM MORLEY, BOTH OF
LEICESTER, ENGLAND.

CIRCULAR-KNITTING MACHINE.

1,358,264.

Specification of Letters Patent. Patented Nov. 9, 1920.

Application filed July 1, 1920. Serial No. 393,413.

To all whom it may concern:

Be it known that we, SAMUEL TIMSON and HARRY MORLEY TIMSON, subjects of the King of Great Britain, residing at Leicester, 5 in the county of Leicester, England, have invented new and useful Improvements in or Relating to Circular-Knitting Machines, of which the following is a specification.

This invention relates to circular knitting machines and concerns yarn changing means especially, though not necessarily exclusively, applicable to rib machines for producing horizontal stripes, running in a splicing thread when making a welt, and like 15 purposes.

The invention, which comprehends mechanism for automatically changing the knitting yarn and severing and clamping the yarn withdrawn during the knitting operation, is applicable to machines of the stationary and revolving cylinder type having one or more feeders, but it is mainly intended for use on a multiple feeder rib machine.

The invention consists of yarn changing means comprising a pair of yarn-guides each movable for yarn feeding and withdrawing purposes, and a yarn severing and clamping device, said yarn-guides being operated in such a manner that between the introduction of a non-knitting yarn and the withdrawal of the knitting yarn a certain amount of knitting is allowed to take place and the severing and clamping device being operated in association with the yarn-guides so that while one yarn is knitting, the end of the non-knitting yarn is held, said end being released after movement of the non-knitting yarn to the feeding position, and the yarn withdrawn from the knitting position being subsequently severed and clamped, characterized by the feature that the actuating means of the movably yarn-guides include rock levers adapted to be operated by a member movable to different operative positions, said levers being arranged so that the member will, in each of its operative positions, actuate the forward end of the rock-lever and the rear end of the other rock lever thereby moving the inoperative yarn guide to the feeding position and moving the operative yarn guide to the non-feeding position.

The invention will be particularly de-

scribed with reference to the accompanying drawings which show a concrete example.

In the drawing:

Figure 1 is an elevation of the upper part of a circular rib knitting machine fitted with yarn changing, severing and clamping means according to the present invention.

Fig. 2 is an inside face view of the gapped plate.

Fig. 3 is a front view of the yarn severing and clamping device.

Fig. 4 is a perspective view of the slide removed from the device shown in Fig. 3.

Fig. 5 is a plan of the essential parts of the arrangement shown in Fig. 1.

Fig. 6 is an elevation of the yarn changing means viewed from the right of Fig. 1.

Throughout the drawings like parts are designated by the same reference characters.

In the example shown, the invention is applied to a circular rib knitting machine of the stationary cylinder type and having two or more feeders only one of which is shown in the drawings. Referring to Figs. 1 and 5, the cam box 1 rotates within the fixed bed 2 about the needle cylinder 3 above which is carried the stationary dial 4 in the usual manner. According to the invention there is provided at each feeder a pair of movable yarn-guides mounted on the cam box 1, and a yarn severing and clamping device mounted on the dial cap 5. Conveniently the yarn guides consist of bars 6, 6^a disposed radially and substantially horizontally and having at their ends nearest the needle cylinder tubular guides 7, 7^a for the respective yarns 8 and 8^a. The bars are supported approximately centrally by carrier levers 9, 9^a, while their rear ends are connected to swinging levers 10, 10^a. The carrier levers 9 and 9^a are fulcrumed at 11 and 11^a while the swinging levers 10 and 10^a are fulcrumed at 12 and 12^a, all said fulcrums being carried on a bracket 13 attached to the cam box 1 by a screw 14. By means of the carrier lever each bar is carried backward and forward relatively to the cylinder needles 15 during which movements it is caused, by reason of its connection with the swinging lever to rock on its carrier lever so that the tubular yarn-guide 7 is lifted over the top of the cylinder needle. The movements of the points of connection of the carrier lever and swinging lever with

100
105

the bar are indicated by dotted arcs in Fig. 1.

The bars 6, 6^a and their associated levers are, as shown in Figs. 5 and 6, arranged on opposite sides of the bracket 13 and it is to be understood that each bar is movable independently of the other in the manner described. Attached to the bracket 13 is a T member 16 (Figs. 1 and 6) between the arms of which and pins 17, 17^a on the levers 10, 10^a springs 18, 18^a are arranged and serve to hold the respective guides 7, 7^a in the feeding and non-feeding positions, which are determined by stop pins 19, 19^a (Figs. 1, 5 and 6) between which the swing levers work. In Figs. 1 to 5 the guide 7 is shown in the feeding position while the guide 7^a occupies the non-feeding position.

The yarn-guides lay their yarns for feeding purposes in a gap 20 formed in the plate or latch guard 21 (Figs. 1, 2 and 5) said gap being shaped and positioned relatively to the cylinder needles 15 to replace the usual feed hole. This feeder plate is conveniently supported by the aforesaid bracket 13 to which it is attached by screws 22 (Fig. 1).

Mounted horizontally on the bracket are two rock levers 23, 24 (Figs. 5 and 6) arranged to turn upon a vertical and approximately centrally disposed axis conveniently formed by the screw 25. These rock levers are operatively connected each with one of the carrier levers, the rock lever 23 being connected by a link 26 (Fig. 1) to the carrier lever 9, and the other lever 24 being connected to the lever 9^a by a similar link 26^a (Fig. 6). At each end the rock levers are provided with a nose to engage by contact with a stationary operating member as the cam box revolves. These comprise projections 27, 28 on the rock lever 23, and similar projections 29, 30 on the rock lever 24, see Figs. 5 and 6. The contact of the nose or projection at one end of the rock lever with the operating member turns the rock lever on its pivot 25 to move the yarn guide to the yarn feeding position, and a similar operation of the opposite end of the rock lever moves the yarn guide to withdraw the yarn from the needles as will be hereinafter more fully explained.

The stationary operating member conveniently consists of a roller 31 (Figs. 1, 5 and 6) mounted upon the upper end of a post 32 slidable through a bearing 33 on the machine bed 2. The roller 31 is adjustable vertically to different horizontal planes, as indicated in Fig. 6, by an actuation of the post 32 this being effected by intermediate means operable from a pattern mechanism which means and mechanism may be of any suitable form.

By reference to Fig. 6 it will be seen that although the rock levers, 23, 24 occupy dif-

ferent horizontal planes, they are so formed that the front end of each lever is situated in the same horizontal plane as the other end of the opposite lever, that is to say, the nose 27 of the lever 23 is substantially level with the nose 30 of the lever 24, and the nose 29 of the lever 24 is substantially level with the nose 28 of the lever 23. The result of this is that in each of its operative positions the operating member will move first one end of the lever and then the other end of the opposite lever. In this manner one rock lever is first actuated to carry the non-knitting yarn to the needles and then the other rock lever is actuated to withdraw the knitting yarn, the distance between the said ends of the levers determining the interval between the introduction of one yarn and the withdrawal of the other.

The roller 31 is arranged to occupy a neutral or inoperative position where it is below the rock levers as shown by full lines in Figs. 1 and 6. In one operative position indicated by the dotted lines 34 in Fig. 6, the roller is situated in the path of the projections 29 and 28 of the respective rock levers 24 and 23. In another operative position indicated by the dot and dash lines 35, the roller is situated in the path of the projections 27 and 30 of the respective rock levers 23 and 24. The cam box revolves in the direction shown by the arrow in Fig. 5, and assuming the yarn guides 7 and 7^a to occupy the positions shown and the roller 31 to be moved to the first operative position 34 (Fig. 6), then when the rock levers pass the roller, the nose 29 of lever 24 will, by contact with the roller, turn said lever and thereby, through the link 26^a and carrier lever 9^a, move the guide 7^a from the non-feeding to the feeding position after which the nose 28 of lever 23 will, by contact with the roller, turn said lever 23 so that by the link 26 the carrier lever 9 will be actuated to move the guide 7 to the non-feeding position. It will be understood that when on passing the roller 31 one end of either rock lever is moved inward, the opposite end of said lever simultaneously moves outward, but being situated on a different horizontal plane is not acted upon by the roller until the latter is moved to the other operative height.

The yarn severing and clamping device consists of a block 36 (Figs. 1, 3 and 5) 120 let into and attached to the dial cap 5 and having in its front vertical face a slide 37, best seen in Fig. 4. The block 36 has formed in it a gap 38 (Figs. 3 and 5) for the reception of the lower tubular ends of the yarn-guides 7, 7^a when they move to the inoperative position represented by the member 7^a in Figs. 1 and 5. The slide 37 works across the front of the gap 38 and has formed upon it a finger 39 (Figs. 3 and 4) 130

the edge 40 of which is sharpened to constitute a shearing edge and arranged to operate, as the slide moves toward the left, in conjunction with a similarly sharpened edge 41 on a plate 42 (Figs. 3 and 5) to sever the yarn. The plate 42 is fastened to the front of a spring controlled bolt 43 arranged in the block 36 whereby the cutting edge 41 is held in close contact with the coöoperating edge 40. The side 44 of the finger 39 also operates in conjunction with a cheek 45 on the block to serve as a clamp to hold the end of the yarn after severance. The slide 37 is actuated by an arm 46 (Figs. 1 and 5) fast with a lever 47 pivotally mounted on the bracket 13 said lever being controlled by a spring 48 (Fig. 6) so that normally the slide is maintained with the clamp members 44 and 45 closed as indicated in Fig. 5. An arm 49 attached to the lever 47 (Figs. 1 and 5) is connected by a link 50 to the free end of an actuating lever 51 situated between the rock levers 23, 24 (Fig. 6) mounted to turn upon the screw 25. This lever 51 is arranged so that a foot 52 thereon (Figs. 1, 5 and 6) occupies a position to make contact with the roller 31 as the cam box revolves, and when this occurs, the lever 51 is thereby moved so that by the link 50 and arm 49, the arm 46 is actuated to move the slide in the arrow direction (Fig. 5) to separate the clamp members and also the shearing members as shown in Fig. 3. The foot 52 of the lever 51 is arranged in such a position between the two rock levers 23, 24 and relatively to the projections thereon, that when the roller 31 is in either of its operative positions 34 or 35 it will operate the slide actuating lever 51. Further, the said foot 52 is disposed so that it will make contact with the roller after the latter has moved the nose 27 or 29 and thereby brought the inoperative yarn-guide to the feeding position and before the nose 30 or 28 is operated to move the operative yarn-guide to the inactive position.

In the operation of the complete mechanism, when the knitting yarn is to be changed, the roller 31 is raised by the pattern mechanism from the neutral position to one of the operative positions 34, 35 so as to be in the circular track of the rock lever of the yarn guide which is in operation. When the nose on the forward end of this rock lever passes in contact with the roller, the non-knitting yarn, is carried from the back of the cylinder needles 15 and laid in the gap 20 so that it is taken by the cylinder needles in conjunction with the knitting yarn, its end meanwhile remaining clamped between the parts 39 and 45. When the foot 52 of the actuating lever 51 passes in contact with the roller 31, the slide 37 is actuated to separate the clamp members and thus release the end of the yarn, and also move the

cutting edge 40 away from the edge 41. After this, and while the foot 52 is still under operation by the roller 31, the nose on the rear end of the other rock lever passes in contact with said roller whereby the other 70 yarn-guide is moved to raise its yarn from the gap 20—thus withdrawing it from the needles—and lay it between the separated cutting edges and clamping members. When the actuating lever 51 passes from contact 75 with the roller 31 the slide 37 under the influence of the spring 48 moves to the normal position thereby severing the yarn between the edges 40, 41 and clamping the end between the parts 39 and 45. 80

A roller such as 31 may be furnished for each feeder of the machine or one of such members may serve for all the feeders, it being understood that yarn changing mechanism of the kind herein described may be 85 furnished at each of the feeders.

In the application of the invention to a machine of the type wherein the dial cap and the cam box are stationary, any suitable means operable from the pattern mechanism 90 or by or from a member rotating with the needle cylinder may be employed to actuate the yarn guides and the severing and clamping slide.

When the invention is applied to machines 95 which are not equipped with a dial, a suitable member adapted to constitute an equivalent support is provided for carrying the severing and clamping device.

What we claim then is:— 100

1. For circular knitting machines of the kind herein referred to, yarn changing means comprising, in combination, a pair of yarn-guides each movable for yarn feeding and withdrawing purposes, and actuating means for the yarn-guide comprising a rock lever for each of said guides and a single operating member for said levers movable to different operative positions, said levers being arranged so that the member will, in each of its operative positions, actuate first the forward end of one rock lever and then the rear end of the other rock lever thereby moving the inoperative yarn-guide to the feeding position and moving the operative yarn-guide to the non-feeding position. 115

2. In a circular knitting machine of the class described, the combination of a pair of yarn guides each movable to yarn feeding and withdrawing positions, a rock lever for actuating each of said guides, a single operating member for said levers movable to different operative positions, said levers being so relatively located that the operating 120 member will in each of its operative positions actuate first the forward end of one rock lever and then the rear end of the other rock lever thereby to reverse the positions of the yarn guides, a yarn severing and 125

clamping device, and means between said device and said operating member for operating said device in such sequence with relation to the operation of said yarn guides that the end of the yarn in the non-feeding guide is clamped and when the position of the guide is reversed the yarn in the feeding guide is severed.

3. For circular knitting machines of the kind herein referred to, yarn changing means comprising, in combination, a pair of yarn-guides each movable for yarn feeding and withdrawing purposes, actuating means for the yarn-guides consisting of rock levers and a single operating member for said levers movable to different operative positions, said levers being arranged so that the member will, in each of its operative positions, actuate first the forward end of one rock lever and then the rear end of the other rock lever thereby moving the inoperative yarn-guide to the feeding position and moving the operative yarn-guide to the non-feeding position, a yarn severing and clamping device, and means for actuating said device and comprising a rock lever arranged in such relation to the aforesaid rock levers of the yarn-guides as to be operated by the same operating member after the latter has actuated the forward end of one rock lever and before and during the actuation of the rear end of the other rock lever, substantially as described.

4. For circular knitting machines of the kind herein referred to, yarn changing means comprising, in combination, a pair of yarn-guides each movable for yarn feeding and withdrawing purposes, rock levers to actuate said guides, a single member movable to different operative positions to actuate said rock levers, said member being arranged so that it will, in each of its operative positions, actuate first the forward end of one rock lever and then the rear end of the other rock lever to change the yarn-guides, a yarn severing and clamping device, and means to operate the same in association with the yarn-guides, substantially as described.

5. For circular knitting machines of the kind herein referred to, yarn changing means comprising in combination, a pair of yarn-guides each movable for yarn feeding and withdrawal purposes, rock levers to actuate said guides, a single member mov-

able to different operative positions to actuate said rock levers, said member being arranged so that it will, in each of its operative positions, actuate first the forward end of one rock lever and then the rear end of the other rock lever to change the yarn-guides, a yarn severing and clamping device, and a rock lever actuated by the aforesaid member in each of its operative positions to operate said device in association with the yarn-guides, substantially as described.

6. For circular knitting machines of the kind herein referred to, yarn changing means comprising, in combination, yarn guides, a bar for each yarn guide, a carrier lever supporting each bar, a spring controlled swinging lever connected to each carrier lever, stop pins between which each swinging lever moves, a rock lever for each yarn-guide, a connection between said rock levers and the respective carrier levers of the yarn-guides, a single horizontally rotatable roller, movable vertically to different positions for operating the rock levers, said rock levers being arranged so that the roller will, in each of its operative positions, actuate first the forward end of one rock lever and then the rear end of the other rock lever thereby moving the inoperative yarn-guide to the feeding position and moving the operative yarn guide to the non-feeding position, substantially as described.

7. For circular knitting machines of the kind herein referred to, yarn changing means comprising, in combination, yarn-guides each movable for yarn feeding and withdrawing purposes, rock levers to actuate said guides, a member movable to different positions to actuate said rock levers, a block provided with a gap for reception of the yarn-guides when in the non-feeding position, a slide movable in the front face of the block, a shearing edge and a clamp member on the slide, a shearing edge and a cheek on the block with which the aforesaid shearing edge and clamp members coöperate, a rock lever operable by the aforesaid member, and connections between said rock lever and the slide to actuate the latter, substantially as described.

In testimony whereof we have signed our names to this specification.

SAMUEL TIMSON.

HARRY MORLEY TIMSON.
